UNITED STATES PATENT OFFICE.

WILLIAM F. BEARDSLEE, OF BOSTON, MASS., ASSIGNOR TO THE MANUFACTURERS' SPECIAL MACHINE COMPANY, OF DANBURY, CONN.

SEWING-MACHINE.

SPECIFICATION forming part of Letters Patent No. 355,053, dated December 28, 1886.

Application filed February 4, 1886. Serial No. 190,815. (No mod.1.)

To all whom it may concern:

Be it known that I, WILLIAM F. BEARDSLEE, of Boston, county of Suffolk, and State of Massachusetts, have invented an Improvement 5 in Sewing-Machines, of which the following description, in connection with the accompanying drawings, is a specification, like letters on the drawings representing like parts.

This invention has for its object to improve 10 that class of machines wherein two eye-pointed thread-carrying needles penetrate the material, loops from both needles being caught and held by an oscillating looper while the needles ascend, the said looper holding both the said 15 loops in such position that they are both entered by but one of the needles at the next descent of the needle-bar, the result being the formation of a whip-stitch from two threads carried by the said two eye-pointed needles.

20 My improvements in the class of machines referred to relate more especially to mechanism for operating the looper and to means for holding the two needles in the needle-bar.

Figure 1 in side elevation shows a sewing- 25 machine embodying my invention; Fig. 2, a left-hand end elevation of Fig. 1, the cloth-plate being in section. Fig. 3 is a plan view with the upright arm and link broken away and the cloth-plate removed; Fig. 4, a face 30 view and section of the cam for operating the looper, the said figure showing the adjustable tapering roll in the groove of the cam; Fig. 5, details of the looper; Fig. 6, a diagram showing parts of the two needles, the hook, and the 35 end of the feed-bar and its operating-eccentric; and Fig. 7 is a sectional detail in the line x^x , Fig. 2.

The frame-work A, needle-actuating arm A', link A², main rotating shaft A³, feed-bar A', 40 and cloth-plate A⁵ are substantially the same as in the Willcox & Gibbs sewing-machines.

The forward and backward movements of the feed-bar are obtained through a rocker, B, attached to a rock-shaft, B', and operated by 45 a link, B², having at one end an eccentric-strap, which embraces an eccentric, B³, in usual manner.

The frame-work of the machine has attached 50 to it by screws α a bracket, b, the said bracket having at its front side two bearings, b' b', for the looper-shaft c, and extending backward an

arm, b², (see Fig. 1,) which has at its end a bearing, b³, for the reception of the rock-shaft d, to which is attached the segment d', which engages the bevel-gear c', fast on the looper-shaft c, the said looper-shaft being oscillated and carrying the looper c², the shank of which is adjustably attached by the set-screw c³ to a head, c⁴, forming an integral part of the looper-shaft c.

The rock shaft d, at its inner end, has attached to it by screw d² an arm, d³, provided with a conical stud, d⁴, having a screw-threaded shank, d⁵, by which the said stud may be moved or adjusted longitudinally with relation to the 65 said arm, the stud being retained in adjusted position by a set-nut, 2, the conical portion of the said stud receiving upon it a conical roll or shell, which enters a tapering groove in the cam e, attached to the main shaft A³ by the 70 screw 4, adjustment of the conical stud enabling wear between it and the said cam to be compensated for. The shaft d has adjustably attached to it, by suitable screws, two collars, 75 5 6. (Best shown in Fig. 1.) The set-screws holding these collars upon the shaft may be loosened, and the said shaft may thereafter be moved longitudinally to compensate for wear between the segment d' and the bevel-gear c', after which the said collars will be fastened in 80 place. Sufficient space is left between the hub of the arm d³ and the end of the bearing b³ to allow for this longitudinal movement of the shaft d.

The needle-bar at its lower end is drilled to 85 leave two holes for the reception of the shanks of the two eye-pointed thread-carrying penetrating-needles g g', the said two holes being so bored as to intersect, as shown in Fig. 8, and enable the shanks of the two needles placed 90 7 therein to come in contact.

The needle-bar is bored from its side, forming a clear opening to intersect the central bore, and thereby permit the screw h, engaging a screw-thread in a collar, h', to be passed into 95 the said clear opening and act against the shank of the centermost needle, the said screw, when turned to enter the said collar and act against the centermost needle, also causing the collar to be drawn against the needle-bar at its rear 100 side, the said screw and collar, put together as described, effectually holding both needles in

the needle-bar; or, in other words, one screw is made available to hold both needles.

The eye of one needle is set lower than the eye of the other needle, so as to enable the loops in the thread carried by the said needles to be entered by the oscillating looper c^2 , the latter being made adjustable in its holding-block c^4 , to thereby enable the looper and its shoulder 10 to properly co-operate with the loops of needle-thread under any adjustment of the parts.

The stitch made by the mechanism herein described is substantially that made by the machine described in application, Serial No. 15 167,679, filed June 4, 1885, made by A. Morehouse.

I claim—

1. The needle-bar, its two eye-pointed reciprocating needles, the looper, its rock-shaft provided with a pinion, and the sector, combined with the rock-shaft d and means, substantially as described, to oscillate it.

2. The shaft A^3 , its attached cam having a

tapering groove, and the rock-shaft d , having an arm, d^3 , and its attached adjustable conical 25 stud, combined with the segment d' , the looper, the looper-shaft, and its attached bevel-gear, substantially as described.

3. The needle-bar provided at its lower end with two intersecting parallel holes for the reception of the shanks of two needles, and with a clear opening for the free entrance of a screw, and two needles in the said holes, with their shanks in contact, combined with a collar and a single screw, the latter acting upon the shank 30 of one needle, and through it and the collar upon the other needle, the collar being threaded for the reception of the said screw, substantially as described.

In testimony whereof I have signed my name 40 to this specification in the presence of two subscribing witnesses.

WILLIAM F. BEARDSLEE.
